DESIGN FOR A WALKING-SKIRT.

2109

2109

UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A WALKING-SKIRT.

SPECIFICATION forming part of Design No. 18,320, dated May 15, 1888.

Application filed April 20, 1888. Serial No. 271,346. Term of patent 3½ years.

To all whom it may concern:

Be it known that I, LIZZIE Roys, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking skirt that displays a flat drapery falling to the edge of the gores and exhibiting three deep kilt plaits at the left side of the front; a tablier drapery that displays draping plaits just above the plaits in the flat drapery and also in the side

edges, and falling with the effect of a pannier on the right hip and in a point to the edge of the skirt at the left side; narrow kilted panels on either side of the back, and a full back drapery that displays draping plaits in its side edges and loopings at the center.

What I claim as my invention, and desire to secure by Letters Patent, is—

The design for a lady's walking skirt, as shown in the engraved prints accompanying this specification.

LIZZIE ROYS.
